UNITED STATES PATENT OFFICE.

CHARLES T. HAMPTON, OF DES MOINES, IOWA.

METHOD OF SPLICING A TUBE AND THE PRODUCT THEREOF.

1,342,441.

Specification of Letters Patent.

Patented June 8, 1920.

Application filed March 10, 1919. Serial No. 281,605.

To all whom it may concern:

Be it known that I, CHARLES T. HAMPTON, citizen of the United States of America, and resident of Des Moines, Polk county, 5 Iowa, have invented a new and useful Method of Splicing a Tube and the Product Thereof, of which the following is a specification.

The object of this invention is to provide 10 an improved tube splice and method for splicing tubes and particularly rubber or composition inner tubes for vehicle tires.

My invention consists in the construction, arrangement and combination of parts and 15 the method of using them as hereinafter set forth, pointed out in my claims and illustrated by the accompanying drawing, in which—

Figure 1 is an elevation of an inner tube 20 to which my improvement is applied. Fig. 2 is an elevation of a portion of the same tube, on an enlarged scale, illustrating one step in my improvement in splicing. Fig. 3 is a longitudinal section through the wall of 25 the tube and splice member, the parts being greatly exaggerated or magnified, showing the relation of the parts in the completed article. In Figs. 2 and 3 portions are broken away to economize space.

30 In the construction of the device as shown the numeral 10 designates a sleeve, preferably made of vulcanized rubber, or other suitable substance or composition, flexible, elastic, and of the same general character as 35 inner tubes of vehicle tires. The sleeve 10 is tubular, and preferably curved throughout its length on the arc of a circle conforming to that of the tube with which it is to be used and the ends of said sleeve are skived or 40 beveled at 24, 25 on the inside, as indicated by dotted lines in Fig. 3. The sleeve 10 is of a diameter adapting it to receive in its ends smoothly and overlap end portions of an "inner" tube 11. Inner sleeves 12, 13, of 45 similar substance and character and alike in form and structure, but of less diameter, with the sleeve 10, are mounted end to end and spaced apart within the sleeve 10, and inner end portions 26, 27 of said inner sleeves 50 are vulcanized or otherwise rigidly, and in homogeneous manner, secured to said sleeve 10. Outer end portions of the inner sleeves 12, 13 are free from the inner face of the sleeve 10 and the ends of said inner sleeves 55 are skived or beveled on the inside or out-

side, as desired, as at 16, 17. The outer surfaces 18, 19 of the outer end portions of the inner sleeves 12, 13 (free from the inner surface of the sleeve 10) are coated with gum or adhesive substance adapted to receive another and further coating as hereinafter set forth, and said primary and permanent coating is protected from contact with the inner face of the sleeve 10 by an overlay (not shown) of fabric in a manner now 60 common and well known in association with tube patches. The end portions of the sleeve 10 extend materially beyond the outer ends of the inner sleeve 12, 13 and the inner faces 20, 21 thereof (free from the outer faces of 65 the outer end portions of said inner sleeves) likewise are coated primarily and permanently with a substance adapted to receive a further coating of liquid cement, and said faces 20, 21 are likewise protected by over- 70 lays of fabric (not shown).

In carrying out my improved method and in the practical use of my improved device, a damaged tube 11 (such a tube as may have been torn wholly or largely asunder) is 80 placed alongside one of my devices, (the ends of the sleeve 10 of the latter being turned back as shown in Fig. 2) and a portion of the tube 11 (including the fracture) 85 corresponding in length with the space between the shoulders 14, 15, is cut away by transverse amputation on radial lines. The end portions of the tube 11 are then turned back and cleaned and buffed as to their inner (temporarily outer) faces and a coating of 90 liquid cement is applied thereto and permitted to air-dry. The fabric overlays are removed from the outer ends 18, 19 of the spaced inner sleeves, and the surfaces thus exposed are coated with liquid cement and 95 allowed to air-dry. Then the ends of the tube 11 are unrolled upon the end portions of the inner sleeves and pressed firmly thereon. Then the outer faces 22, 23 of the end portions of the tube 11 are cleaned and 100 buffed and coated with liquid cement which is allowed to air-dry. Then the back-turned end portions 20, 21 of the sleeve 10 are uncovered by removal of the fabric overlays therefrom, are treated to a coating of liquid cement which is allowed to air-dry, 105 and, then, are unrolled upon the outer surfaces 22, 23 of the end portions of the tube 11 and are pressed firmly thereon. The result will be as illustrated in Fig. 1, the rela- 110

tion of the parts, overlapping and in adhesive contact being shown (exaggerated) in Fig. 3.

The resultant splice is of slightly greater diameter than the tube 11; but it does not wrinkle, crimp, flute or gore the ends of the tube; hence it is efficacious in making a repair.

I claim as my invention—

- 10 1. A tube splice comprising an outer sleeve, an inner sleeve connected thereto, throughout a portion only of its length, said sleeves being arranged for the reception between portions thereof of the end of a tube, faces of said sleeves being gum treated.
- 15 2. A tube splice comprising a sleeve, inner sleeves therein and placed end to end, the inner sleeves being secured throughout portions only of their lengths to the outer sleeve, the free portions of said sleeves being gum-treated on adjacent faces.
- 20 3. A tube splice comprising an outer sleeve, inner sleeves therein and placed end to end and spaced apart, the inner sleeves being secured permanently throughout portions only of their lengths to the outer sleeve, the free portions of said sleeves being gum-treated on adjacent faces.
- 25 4. A tube splice comprising an outer sleeve, inner sleeves therein and placed end to end and spaced apart, the inner sleeves being secured permanently throughout portions only of their lengths to the outer sleeve, the outer sleeve projecting at its ends beyond the outer ends of the inner sleeves, the free

portions of said sleeves being gum-treated on adjacent faces.

5. The method of splicing a tube, which consists in inserting inner sleeves in end portions of said tube, and overlapping end portions of an outer sleeve on said end portions of said tube, adjacent faces of said tube and sleeves being gum-treated, securing outer faces of said inner sleeves to inner faces of said tube, and securing inner faces of said outer sleeve to outer faces of said tube.

6. A tube splice comprising a sleeve, inner sleeves therein and placed end to end, the inner sleeves being secured throughout portions only of their lengths to the outer sleeve, the free portions of said sleeves being gum-treated on adjacent faces, end portions of said sleeves being beveled or skived.

7. A tube splice comprising an outer sleeve, and inner sleeves therein and placed end to end and spaced apart, the inner sleeves being secured permanently throughout portions only of their lengths to the outer sleeve.

8. A tube splice comprising an outer sleeve and inner sleeves therein and placed end to end and spaced apart, the inner sleeves being secured permanently throughout portions only of their lengths to the outer sleeve, end portions of said sleeves being beveled or skived.

Signed at Des Moines, in the county of Polk and State of Iowa this 7th day of March, 1919.

CHARLES T. HAMPTON.
